UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

40,946.

Specification for Design.

Patented Oct. 18, 1910.

Application filed August 11, 1910. Serial No. 576,778. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming a part thereof.

The figure is a front elevation of a burial-casket handle showing my new design, one of the tip ends of the handle-bar being broken away and such handle-bar being a

short one that is used with a pair of closely adjacent lugs and arms at both ends of the side faces of the casket, or in triple pairs along both side faces of the casket, the number of pairs depending on the length and weight of casket.

I claim:—

The ornamental design for a burial-casket handle as shown and described.

CHARLES BLESCH.
